(57) **CLAIM**

The ornamental design for a stem for an article of stemware, as shown and described.

DESCRIPTION

FIG. 1 is a front elevational view of a stem for an article of stemware showing my new design; the rear elevational view being the same;

FIG. 2 is a first side elevational view thereof;

FIG. 3 is a second side elevational view thereof;

FIG. 4 is a top view thereof; and,

FIG. 5 is a bottom view thereof.

The broken lines in the drawings are for illustrative purposes only and form no part of the claimed design.
